SEAT COVER

Julius Levi, Chicago, Ill., assignor to
Sam Pass, Chicago, Ill.

Application December 9, 1933, Serial No. 701,583

1 Claim. (Cl. 155—182)

This invention relates to improvements in seat covers.

One object of the invention is to provide seat covers such as for automobile seats, which are provided with panel inserts of relatively coarse material which not only has desirable wearing qualities but also provides a cooler seat and back rest than the cloth material of which the remainder of the cover is formed.

10 A further object of the invention is to so secure the inserted panels at their edges to the adjacent cloth portions by folding the edges of the latter material over both sides of the edges of the panels that raveling of the panel is prevented, and by 15 similarly joining adjacent edges of the cloth material the use of separate binding is obviated, and the seams of the covers are finished on both sides so they may be turned inside out when the outer side has become soiled.

20 In the drawing illustrating the embodiment of the invention

Figure 1 is a perspective view of a conventional automobile seat having my improved covers thereon.

25 Figure 2 is an enlarged fragmentary elevation showing in different planes the construction of the covers at a corner of the inserted panel.

Figure 3 is a view similar to Figure 2, but viewed from the opposite side of the cover.

30 Figure 4 is a sectional view taken on line 4—4 of Figure 1.

Figure 5 is a sectional view taken on line 5—5 of Figure 1.

35 Figure 6 is a sectional view taken on line 6—6 of Figure 1.

In the drawing, 10 indicates generally a cover for a seat and 11 represents a cover for the seat back.

Referring to the seat cover, it will be seen that 40 the same is provided with a central panel 12 formed of relatively coarse woven material. This material preferably is formed of paper or fibrous material, and is well known in the trades. This material is durable and being relatively coarse, 45 provides a cool seat in the summer time, and thus my improved covers render unnecessary the use of the conventional straw pads frequently employed by motorists during warm weather.

Secured to the ends of the panel 12 are upper 50 end sections 13 and 14, the forward portions of which, as shown in Figure 1, extend approximately to the forward edge of the seat. The rear ends of the sections 13 and 14 extend downwardly to the lower margin of the seat.

55 Attached to the forward edge of the panel 12

at seam 15 is a front cloth section 16. This section has end extensions which form the end sections 17 and 18 which are secured to sections 13 and 14 at the seams 19 and 20 respectively. The seams 19 and 20 will be disposed at the end edges of the seat, as shown.

A rear section 21 is secured at seam 22 to the panel 12 and at its ends to the adjacent rear edges of the panels 13 and 14. The bottom edges of the sections 16 and 17, 18 and 21 may be provided with a gathering string 23 by means of which the cover is secured in place. Tie strings may, of course, be employed if desired.

Figures 4, 5 and 6 show the manner of folding the cloth material to form the seams which are finished on both sides. Thus in Figure 4 it will be seen that the margin of section 13 has its free edge 13a stitched at 24 to the panel 12. The material is then folded over the layer 13 as shown in Figure 4, and brought in a double fold beneath the edge of panel 12 and stitched thereto at 25, the latter stitches extending through the four layers of the cloth material of the section 13 and through the panel 12. An additional row of stitches 26 may be provided, if desired.

This manner of folding the cloth material is employed at all the seams where the cloth material of the various cover sections are attached to the panel 12.

Figure 5 shows the formation of the seam 19 which is typical of the seams where two cloth sections are attached together. Thus it will be seen that the margin of the section 17 is enclosed between two double folds of the section 13, and stitched in the manner described above in connection with Figure 4.

Figure 6 is a view taken on line 6—6 of Figure 1, and corresponds with the arrangement of the folds shown in Figure 4.

Figures 2 and 3 are upper and lower plan views 40 respectively illustrating the fold of the materials at the corner x of the panel 12.

This manner of folding the margins of the cloth sections over the edges of the panel 12 firmly secures the parts together with the edges 45 of the cloth sections and of the panel 12 disposed inwardly of the seam to prevent fraying or loosening of the same and forms a finished seam on both sides of the cover. Thus when one side of the cover has become soiled, it may be turned wrong side out and replaced on the seat cushion for further use.

The panel 12 extends only over the central portion of the top of the seat cushion and does not 55

fold over any of the edges of the cushion nor is it folded in forming the seams.

The cover 11 for the seat back is constructed on similar principles. This back cover is provided with a coarse woven fibrous panel 27 being attached at its ends to the cloth sections 28 and 29 at seams 30 and 31 respectively. These seams are similar to those shown in Figures 4 and 5.

Along the upper edge of the panel 27 is attached a cloth section 32 at seam 33 and at the lower edge of the panel is attached the cloth section 34 at seam 35. Cross sections through these latter two mentioned seams will correspond with the structure shown in Figures 4 and 5. The cover sections 11 may be constructed to form an envelope or sack which slides down over the back of the seat and may be secured at the lower end thereof by a gathering string or any other desirable means.

20 The section 32 may have end extensions 36 and 37 which extend down along the ends of the back and are attached to the sections 28 and 29 at the seams 38 and 39, which are formed similar to the seams shown in Figure 5. The sections 32, 25 36 and 37 and the section extending over the back of the seat, not shown, may be made of one piece of cloth or of smaller pieces attached together by seams finished on both sides, if desired.

30 This construction provides a cover for the seat back which may also be turned wrong side out when soiled, as above mentioned.

The improved seat covers render unnecessary the use of the straw pads frequently used by

motorists during warm weather, since the relatively coarse paper or fibrous material of which the panels 12 and 27 are formed makes cooler seats and back rests than does the cloth of which the remaining portions of the covers are made. 5

The construction of the seams as described avoids any folding of the margins of the sections 12 and 27, and thus reduces likelihood of breaking or tearing the panels along the seams.

While I have shown and described an embodiment of my improvements for the purpose of illustration, I do not wish to be restricted specifically thereto except as so limited by the appended claim.

I claim:

A cushion cover comprising a panel of relatively coarse fibrous material adapted to cover the central portion of a seat cushion and terminating short of the marginal edges thereof, cloth sections secured to the ends of said panel and 20 extending across the ends of the cushion from the front edge thereof downwardly over the rear of the cushion at the ends thereof, a second cloth section secured to the rear margin of said panel and at its adjacent edges to said first mentioned 25 cloth sections, and a cloth section secured to the forward margin of said section and to said first mentioned sections and depending over the forward wall and end walls of the cushion, all said 30 cloth sections being attached at adjacent margins one to another and to said panel by seams finished on both sides whereby the cover can be used either side out.

JULIUS LEVI.
